LUMINOUS DISPLAY OR REFLECTOR SIGN

Jonathan C. Stimson, Chicago, Ill.

Original No. 1,809,761, dated June 9, 1931, Serial No. 650,403, July 9, 1923. Reissue No. 18,166, dated August 25, 1931, Serial No. 544,649, June 15, 1931. This application for reissue December 2, 1937, Serial No. 177,837

21 Claims. (Cl. 40—130)

This invention relates to luminous displays, and more particularly to luminous display or reflector signs.

In the accompanying drawings:

Figures 1 and 2 are a side elevation and a plan view respectively showing an illustrative luminous display or reflector sign embodying this invention.

Figure 3 is a plan showing another embodiment of this invention;

Figures 4 and 5 are views illustrating the principles of operation of a reflector used in the luminous display sign embodying this invention;

Figure 6 is a perspective view of a prismatic plate used in the display sign;

Figures 7, 8 and 9 show different applications of the reflector or prismatic plate in the formation of display characters on the luminous display or reflector sign embodying this invention;

Figures 10, 11 and 12 are enlargements of portions of Figures 7, 8, and 9 respectively, showing the reflecting units forming the outline of the character.

Display signs as heretofore made are of two general types, namely: those in which the light is radiated from lamps forming the display characters of the sign, and those in which the characters are displayed by diffuse reflection from the surfaces of the character on the sign area.

Where the light is radiated directly from the lamps forming the characters, only a small part of the total emitted light is useful; for only a small percentage of the total emitted light from a bulb or a series of bulbs is utilized for display

purposes, keeping in mind that the light from a bulb is radiated in a sphere of which the source forms the center and that the useful light for display purposes forms only a small sector of the sphere. Accordingly since the intensity of the illumination varies inversely as the square of the distance, it necessarily follows that in order to obtain a practical range of visibility, bulbs of relatively high candle power must be used.

Not only is a display sign employing bulbs for direct radiation wasteful in energy, but the maintenance cost in the replacement of bulbs and repairs generally is also high, especially since in order to secure a display of given characters, these characters must be built up by a series of lights requiring a multiplicity of bulbs. Moreover such characters being built up by spaced point sources of light can only approximate the outline of the character, and require high power lamps to make them visible at a dis-

tance. Such signs are, moreover, very expensive to install and operate.

In luminous display signs in which the sign area is painted or formed to provide display characters which are illuminated by directing light from a suitable source or sources onto the sign area, the characters are visible by diffuse reflection. Such reflection fills the entire hemisphere in front of the sign although serving a useful purpose within only a small zone. By reason of the nature of the surface of such a sign a large part of the light is absorbed, even when the sign is painted with ordinary paint. In order to avoid high lights, flat paints are sometimes used resulting in a matte surface. From such a surface the light is even more fully diffused and there is a greater absorption of light. As a result the sign, in proportion to the amount of illumination used is effectively visible at short distances only. Further, even at short distances such signs lack the brilliance of electric signs.

One of the objects of this invention, therefore, is to provide means of creating luminous display or reflector signs in which the light directed on the sign area and more particularly on the display characters, is so emitted or reflected as to be confined within a selected field from which the display characters are visible; this is accomplished in the illustrated embodiments of this invention by reflecting the light from the display characters in the form of a spreading but concentrated beam or beams into that selected visible field.

Another object of this invention is to provide a luminous display or reflector sign having display characters visible from within a selected field, whereby the light emitted from the characters is so concentrated and controlled as to be confined within that field; this is accomplished in the illustrated embodiments of this invention by providing the characters with reflecting surfaces which are so constructed and arranged as to reflect the light impinging thereon from a variety of angles, in the form of a spreading but concentrated beam or beams and into that selected visible field; all in order to display the characters within that field and render the display legible and visible at great distances.

Further objects will appear from the detail description taken in connection with the accompanying drawings.

Generally stated and in accordance with this invention the luminous display or reflecting sign has a sign character or characters provided with

or formed of reflecting units arranged to form the outline or outlines of the character or characters. Each of these units comprises an optical system and has a reflecting area adapted to reflect light incident thereon from a distant source back in the general direction of the light source, irrespective, within limits, of the angle of incidence of the light. The units have means or are constructed to slightly spread the reflected light; that is, the light reflected from the units is so concentrated and controlled as to confine the reflected light within the desired field and to exclude it from outside spaces, in order to render the character or legend legible at great distances. In accordance with this invention the useful light reflected is so controlled as to be concentrated within an included angle of twenty degrees. The reflecting units are usually arranged along the strokes of the character to outline the same. These units may be arranged in clusters along the character.

In accordance with an illustrative embodiment of this invention the reflecting surfaces forming the characters of the luminous display or reflector sign are in the form of triple reflectors constructed as shown and described in Patent No. 1,671,086, issued May 22, 1928.

A central triple reflector comprises three reflecting surfaces arranged to intersect at a common point and such a reflector has the property of reflecting incident beams back to their source irrespective (within limits) of the angle of incidence of such a beam with respect to the axis. Where the triple reflector is a prism causing reflection of the incident beam, the limiting angle of incidence (with respect to the axis) can be increased while the loss of reflected rays is decreased for any given angle of incidence. However, in an optically accurate central triple reflector (in which the reflecting surfaces are at right angles to each other so as to form in effect the corner of a cube and which is provided with optically plane surfaces) the incident beams are reflected directly back to the source. Such a reflector will, therefore, merely produce a "halo" whose annular width at the source is equal to the diameter of the reflecting unit, so that the unit will be observable only when the eye of the observer is close to the source and within the "halo". A reflector of that character, therefore, has no practical utility in a luminous display or reflecting character sign. In the sign embodying this invention the reflected light is spread to reach the eye of an observer located a substantial distance outside of a line connecting the reflecting unit or units with the light source, but the spread is so concentrated and controlled (within an included angle of twenty degrees) as to secure the desired distance legibility and visibility.

The triple reflector described and shown in the patent referred to is so constructed as to reflect the impinging light in the form of a concentrated and controlled spreading beam or beams. This is accomplished in an embodiment of the invention described in the patent referred to, by deviating the reflecting surfaces thereof slightly from true right angular relation and by distorting the surfaces, so as to vary from the true optical surface of a central reflector; specifically stated this latter is accomplished in a prismatic reflector by forming the reflector of pressed glass and by so controlling the degree of polish of the reflecting surfaces as to leave the same sufficiently rough and undulating to secure spread re-

flection. This is illustrated in Figures 4 and 5, where the surfaces of the triple reflector 12 are shown undulating (on an exaggerated scale) so that an incident beam 13 from a source of light 14 provided with a reflector 15 (such as a parabolic reflector) is reflected in the form of a spreading beam which is of uniform intensity, the spread of the beam being controlled by the degree of polish given the reflecting surfaces.

As a practical illustrative embodiment a reflecting area is formed by a prismatic plate 17 of pressed glass, which has formed on the back thereof a series of triple reflecting prisms 18 arranged in contiguous relation, the reflecting surfaces of these prisms being formed by pressing in a suitable mold and the polish of the reflecting surfaces being controlled by the degree of polish given the mold surfaces. Such a prismatic plate has the property of reflecting incident substantially parallel beams of light back past the source in the form of a cone having the plate as the apex of the cone and the source of light in the axis of the cone, regardless of the position of the light source with respect to the reflector within wide angular limit. If the reflecting plate is transparent, reflection takes place through total internal reflection, the angular range through which the transparent total triple reflecting prisms function being sufficient for most display signs. If service conditions require an angular range and quantity of reflection beyond the reflecting range of the transparent prismatic plate, the back or figured face of the plate may be silvered, thus widening the range through which all of the units of the reflector will function.

In the procedure described in Patent 1,671,086 directions are given which will produce units of pressed glass in which the useful reflected light while spread as required, will be so controlled as to be concentrated within an included angle of twenty degrees.

The mold or matrix of the reflector is constructed with the angles approximately accurate, that is, within about one degree of ninety degrees (90°), but not within a second or less as is required in an optical device if a defined undistorted image ("halo") is to be secured. The surfaces of the mold are made as plane as is conveniently possible and are given a degree of polish. If not polished too highly there are minute irregularities in the surfaces that result in a symmetrical spreading of the light as it is successively reflected upon the three surfaces; the irregularities forming a large number of minute reflecting surfaces of different angles, these surfaces varying sufficiently from a true plane to cooperate together in the multiple reflection of the three surfaces so as to spread the light to a degree, but not varying sufficiently from ninety degrees (90°) to scatter the light out of a defined beam or field.

In practice a reflector suitable for most purposes is secured by giving the mold the highest possible polish, the grain of the metal and the effect of shrinkage of the glass in the pressing operation providing a surface, the reflection from which has about the proper amount of spread. As will, however, be obvious the spread of the beam and the uniformity thereof can be controlled by the degree of polish. Where the greatest feasible distance legibility and visibility is required and the observer is located at a point fairly close to the line connecting the reflector with the source of light, then it is necessary to make the mold for the pressed glass reflector

carefully, with a sufficiently high degree of accuracy and polish upon the surfaces so that the reflected beam will be confined to a cone with a small angular spread.

5 In the case of hollow type reflectors of the character described formed by silvered mirrors set at approximately right angles, the surfaces of the silvered glass or other reflecting surfaces can be slightly broken up or left partially unpolished 10 so as to vary from a true plane sufficiently to secure a spreading beam and uniform distribution of the light. This can readily be secured in the case of silvered surfaces of glass by using ordinary window glass for the reflectors, or as a cover 15 glass for the front of the reflector. Where the reflector is made of pressed glass so as to form a transparent solid or prismatic reflector, the front face is in that case conformed to a surface of the mold so as to form a face which deviates from 20 a plane. In these embodiments, therefore, employing silvered window glass for the reflectors, a cover of window glass, or prismatic glass plates formed to shape as described, there is placed in front of the reflecting surfaces, a heterogeneous 25 or irregular refracting medium which will operate to secure a definite spreading beam and uniform distribution of the light.

Each of the units is, therefore, constructed to direct a definite but concentrated spreading beam 30 of substantially uniform intensity into the selected field. Furthermore by the employment of a prismatic construction as shown in Figure 6, in which a series of comparatively small units are arranged in contiguous relation, there will be a 35 composite beam made up from the beams of the several units and they work together to make a more or less rather uniform field, even if the angles in the several units vary from ninety degrees but within the limits described. The several units in such a case cooperate to cause a blending of the beams from the several units, By grouping these reflectors in contiguous relation over the reflecting face, varying orientations of the unit reflectors with respect to any given beam 40 is secured. In view of the fact that the reflector units are arranged in contiguous relation, with each unit constructed as heretofore described, the spreading fields of light from the several units merge into a definite spreading beam. The composite beam from the several reflecting units is, 45 therefore, confined within the selected field.

The application of the reflecting prism to luminous display or reflector signs can be varied to suit requirements. Thus as shown in Figures 55 7 and 10, the characters 19 may be formed of pressed glass having formed on the back thereof of a series of triple reflecting prisms whose reflecting surfaces are formed as heretofore described. These characters may either be used integrally or may be built up of parts, and such characters, or the parts thereof may be secured to a sign area in any suitable manner, it being understood, of course, that these prisms will project from the rear part of the character.

60 65 As shown in Figures 8 and 11, and 9 and 12 the sign area 20 or 21 may be formed of a prismatic plate, either in a single piece or built up from a series of plates, with the reflecting surfaces formed as heretofore described and with 70 the triple reflecting prisms on the back of the sign area. The characters 22 or 23 may then be formed either by coating the sign area, leaving the outlines of the characters exposed as shown in Figures 8 and 11 or by coating the characters 75 leaving the back-ground exposed as shown in Fig-

ures 9 and 12; in the first case, Figures 8 and 11, the characters will appear illuminated while in the second case Figure 9, the background will appear illuminated. It will be understood, of course, that any suitable opaque paint or other 5 coating may be used and this coating may even be translucent and in varying colors so as to present a varied color display. It will, of course, be understood that the total sign area need not be formed as a reflecting surface in either case but 10 only such portions as are required. With this form of sign area the display characters may be varied by removal of the coating and by the application of a new coating.

Figures 1 and 2 show the application of this invention to a location. The frame of the sign 1 is provided with a sign area 24, which is constructed in any manner as heretofore described while the light is directed on the sign area and the display characters thereon from a suitable source, 15 such as one or more lamp bulbs and a reflector 25 which is arranged to project the light on the sign area and the display characters. Any suitable reflector of a high concentrating type, such as a parabolic reflector or a recently developed 20 compensating Mangan mirror may be provided. Such a spot-light is so constructed and arranged such as to throw a spreading beam in order to just cover the sign area and the display characters 25 thereon. From the principles of the reflector as 30 heretofore described, it will be readily seen that the light will be reflected from the display characters in the form of a spreading but concentrated beam or beams and into the selected field (which is, in this case, along the street or thoroughfare 4), which field is that from which the luminous display is visible. It will be understood, of course, that the source of light and impinging reflector 25 and the sign area are so 35 relatively positioned and with respect to the visible field, (with the light source in front of and distant from the sign and located in the field) and that the spread of the beam is controlled as heretofore described, as to confine the reflected light within the visible field. Accordingly maximum efficiency and maximum 40 legibility, visibility and brilliance will be obtained with a minimum of current consumption. It will of course, be understood that a lamp of sufficiently high candle power and a reflector of a 45 sufficient size will be small relative to the sign area so that the sign area and the characters thereon will not be obscured by the presence of the source within the reflected beam; as a practical proposition the light projecting reflector 25 50 will really be invisible at a comparatively short 55 distance from the sign area.

Occasionally a sign is favorably located in a position where it may be viewed without obstruction over a large territory. Such a location may 60 be secured on the top of a high building facing an open public square or at the intersection of wide avenues forming an acute angle. Such a location is shown in Figure 3 where the frame of the sign 1 containing the sign area 24 constructed 65 as heretofore described is located on top of a building 26. In order to secure a distributed field, but still retain a concentrated spreading beam, two or more spot-lights 27 and 28 are located to face the sign area, as by mounting the 70 same on buildings 29 and 30 respectively. The spot-light 27 can be arranged so as to direct a beam 31 on the sign area, which beam will be reflected in the form of a concentrated spreading beam 32, while the beam 33 from the spot-light 28 75

is reflected in the form of a concentrated spreading beam 34. The elements may be so constructed and relatively arranged as heretofore described, that the light will be reflected from the 5 display characters in the form of concentrated spreading beams into the selected visible field, the light from the display characters and incident from the several sources being reflected into selected adjacent visible field areas so as to 10 confine the light reflected from the sign area and the display characters thereon within the visible field. By thus suitably arranging a series of spot-lights and by suitably constructing the sign area and the reflecting surfaces, any desired field of vision 15 may be covered, but the light emanating from the characters is confined within that field.

It will, therefore, be seen that the invention accomplishes its objects, for in accordance with this invention the light emitted from the sign 20 area and the display characters thereon is limited and confined within the visible field. Accordingly the emitted light is transmitted where it will be observable, while it is excluded from outside spaces. It will, therefore, be seen that maximum efficiency is secured even with the losses 25 incident to the employment of reflectors and refractors. Not only is the cost of installation low, but the maintenance cost is low for the reason that the sign area is rugged and will not deteriorate. Nor will the efficiency be impaired on 30 account of the exposure to weather for the reason that the reflecting surfaces are in the rear where they can be protected. Where silvered plates are employed the reflectors may be sealed to the sign 35 board or similarly treated so as to protect them from the weather. If transparent total reflecting plates are used little protection is necessary. It is to be noted in this connection that dust particles, if not in optical contact with the reflecting 40 surfaces, will not impair the reflection but optical contact can readily be avoided by protecting the back against rain. The display sign is so constructed that any suitable characters in the form of letters, figures, illustrations and trade-marks 45 may be employed without resorting to block characters. Moreover any suitable color effect may be obtained as heretofore described by suitable coating applied to the sign area. A desired color effect may also be secured by introducing 50 a color screen in the path of the beam from the spot-light or by passing a varied color screen therethrough. Elaborate flashing effects may also be secured by simply moving an opaque screen in the path of the beam from the spot-light, or by moving one containing perforations 55 designed to secure the desired effect, or by using a semi-transparent screen containing gradations of shading. Furthermore the sign area may be converted and changed readily as heretofore described without great expense.

It will thus be seen that in accordance with this invention there is produced a character sign by which the characters of such a sign are delineated to an observer at great distances by reflection of light directed thereon and that the sign embodying this invention has the following characteristics, namely:—a sign area in a location where it has a narrow useful field of visibility; a distant light source located within the visible field; 60 and a reflecting area comprising a multiplicity of reflecting units arranged to delineate the character of the sign. These reflecting units, however, have the following characteristics, namely:—of directing light back towards a distant light source 65 regardless of the particular position of any unit

on the sign area and regardless of the particular position of the light source with respect to the reflecting area; of distributing that reflected light in a narrow spreading beam, generally confined within the selected narrow visible field of the sign 5 but substantially uniform throughout the field of spread; these reflecting units combining to create a desired legend in the eye of the observer by directing light from such parts of the area as delineate the character of the legend to each 10 point in the narrow selected field of visibility.

While a number of embodiments of this invention have been described and illustrated in an illustrative environment, it will be understood that this invention is susceptible of various embodiments and in various environments in the general art of reflecting signs to perform their useful functions in those environments. It is further obvious that various changes may be made in details without departing from the spirit 20 of this invention; it is, therefore, to be understood that this invention is not to be limited to the specific details shown and described.

The expression "reflecting area" as used in some of the claims comprises the summation of the reflecting areas of the reflecting units as they appear on the sign delineating the character or characters. The statements in the specification and claims to the effect that the reflected light or the useful reflected light will be concentrated 25 within an included angle of twenty degrees, have reference to an angle or cone, with the unit or units from which the reflected beam or beams emanate as the apex of the angle or cone. This, of course, will be the useful angle or cone defining the 30 field in which the sign will be visible to the eye of an observer at great distances (hundreds of feet) and which represents the concentration of the light within the return beam or cone as distinguished from any fringe of such low intensity 35 that it can be disregarded.

Having thus described the invention, what is claimed is:

1. A luminous display sign comprising, a reflecting area on which characters are displayed 45 so as to be visible in front of said area, and a light source in front of but distant from said area and located in a selected field, adapted to direct the light on said area for reflection within the selected field, said reflecting area being composed of reflecting surfaces of an optical system 50 formed and positioned to reflect the light to the selected field, irrespective, within limits, of the angle of incidence of the light, and further constructed to cause a definite spread of the reflected light from said area, but concentrated within an included angle of twenty degrees and so as to confine the reflection within the selected field, in order that the characters may be visible to an observer anywhere within that field.

2. A luminous display sign comprising, a reflecting area on which characters are displayed so as to be visible in front of said area, and a light source in front of but distant from said area and located in a selected field, adapted to direct the light on said area for reflection within the selected field, said reflecting area being composed of a series of reflecting units arranged in contiguous relation, each of said units comprising an optical system constructed and positioned to reflect the light to the selected field, irrespective, within limits, of the angle of incidence of the light, each of said units being further constructed to cause a definite spread of the reflected light therefrom, but concentrated within an included 70 angle of twenty degrees.

- angle of twenty degrees and so as to confine the reflection within the selected field, in order that the characters may be visible to an observer anywhere within that field.
- 5 3. A luminous display sign comprising, a reflecting area on which characters are displayed so as to be visible in front of said area, and a light source in front of but distant from said area and located in a selected field, adapted to direct the 10 light on said area for reflection within the selected field, said reflecting area being composed of a series of reflecting units arranged in contiguous relation, each of said units comprising an optical system constructed and positioned to reflect the light to the selected field, irrespective, within limits, of the angle of incidence of the light, each of said units being further constructed to direct a definite spreading beam of substantial uniform intensity, but concentrated within an 15 included angle of twenty degrees, into the selected field, and the composite beam from the several reflecting units being confined within the selected field, in order that the characters may be visible to an observer anywhere within that field.
- 20 4. A luminous display sign comprising, a reflecting area on which characters are displayed so as to be visible in front of said area, and a light source in front of but distant from said area and located in a selected field, adapted to direct the 25 light on said area for reflection within the selected field, said reflecting area being composed of a series of reflecting units arranged in contiguous relation, each of said units comprising an optical system having reflecting surfaces constructed to 30 direct a definite spreading beam into the selected field, irrespective, within limits, of the angle of incidence of the light, each of said units having means for distributing the reflected light uniformly throughout the field of spread, but concentrate the light within an included angle of 35 twenty degrees, and the composite beam from the several reflecting units being confined within the selected field, in order that the characters may be 40 visible to an observer anywhere within that field.
- 45 5. A luminous display sign comprising, a reflecting area on which characters are displayed so as to be visible in front of said area, and a series of light sources in front of but distant from said area and located within selected, adjacent fields, adapted to direct the light from said area 50 for reflection within the selected adjacent fields, said reflecting area being composed of reflecting surfaces of an optical system formed and positioned to reflect the light to the selected field, irrespective, within limits, of the angle of incidence of the light and further constructed to 55 cause a definite spread of the reflected light from said area, but concentrated within an included angle of twenty degrees and so as to confine the reflection within the selected fields, in order that the characters may be visible to an observer anywhere within those fields.
- 60 6. A luminous display sign having display characters visible from within a selected field, and a light source in front of and distant from said characters, said characters having reflecting surfaces of an optical system arranged in relative angular relation to multiply reflect light impinging thereon and back towards the light source in the form of a spreading beam or beams, but concentrated within an included angle of twenty degrees, said reflecting means being adapted to 65 direct the reflected light into and confine the same to said field in order to display said characters within said field.
7. A luminous display sign having display characters visible from within a selected field, and a light source in front of and distant from said characters, said characters being formed by total reflecting prisms whose surfaces are arranged in angular relation to multiply reflect the light in the form of spreading beams, but concentrated within an included angle of twenty degrees into and confined within the selected field.
8. A luminous display sign having display characters visible from within a selected field, and a light source in front of and distant from said characters, said characters being formed by triple reflecting surfaces which deviate from their true right angular relation adapted to reflect light 15 in the form of spreading beams, but concentrated within an included angle of twenty degrees, into and within the selected field.
9. A luminous display sign having display characters visible from within a selected field, and a light source in front of and distant from said characters, said characters being formed by triple reflecting surfaces adapted to reflect light impinging thereon back towards the light source, and means cooperating with said surfaces adapted 20 to slightly spread the reflected light to a definite degree in the form of a spreading beam or beams, but concentrated within an included angle of 25 twenty degrees so as to confine the same within said field.
10. A luminous display sign having display characters visible from within a selected field, and means in front of and distant from said characters for directing light indiscriminately on said characters, said characters having triple reflectors whose reflecting surfaces deviate from their true right angular relation adapted to reflect the light impinging thereon in the form of spreading beams, but concentrated within an included angle of twenty degrees so as to confine the same within 30 said field.
11. A luminous display sign having display characters visible from within a selected field, and means in front of and distant from said characters for directing light from a source on the display characters, said characters being reflecting surfaces arranged in relative angular relation to multiply reflect the light impinging on said display characters back towards said source, and means cooperating with said surfaces adapted to slightly spread the reflected light to a definite degree in the form of a spreading beam or beams, but concentrated within an included angle of twenty degrees so as to confine the same within 35 said field.
12. A reflecting sign having a sign character provided with reflecting units arranged to form an outline of the character, each of said units comprising an optical system having a reflecting area and adapted to reflect light incident thereon from a distant source back in the general direction of the light source, irrespective, within limits, of the angle of incidence of the light, each of said units having means adapted to slightly spread the reflected light but concentrate the light within an included angle of twenty degrees.
13. A reflecting sign having a sign character provided with reflecting units arranged along the strokes of the character, each of said units comprising an optical system having a reflecting area adapted to reflect light incident thereon from a distant source back in the general direction of the light source, irrespective, within limits, of the angle of incidence of the light, each of said units having means adapted to slightly spread 40
- 45
- 50
- 55
- 60
- 65
- 70
- 75

the reflected light but concentrate the light within an included angle of twenty degrees.

14. A reflecting sign having a sign character provided with clusters of reflecting units arranged to form an outline of the character, each of said units comprising an optical system having a reflecting area adapted to reflect light incident thereon from a distant source back in the general direction of the light source, irrespective, within limits, of the angle of incidence of the light, each of said units having means adapted to slightly spread the reflected light but concentrate the light within an included angle of twenty degrees.

15. A reflecting sign having a sign character provided with clusters of reflecting units arranged to form an outline of the character, each cluster being composed of a series of units arranged in contiguous relation, each of said units comprising an optical system having a reflecting area adapted to reflect light incident thereon from a distant source back in the general direction of the light source, irrespective, within limits, of the angle of incidence of the light, each of said units having means adapted to slightly spread the reflected light but concentrate the light within an included angle of twenty degrees.

16. In a reflecting sign, the combination with a reflecting area consisting of a number of prisms, whose opposite sides meet at substantially right angles at their apices and which are adapted to reflect light incident thereon from a distant source back in the general direction of the light source and which have means adapted to slightly spread the reflected light, but concentrate the light within an included angle of twenty degrees, of means for blocking out portions of the reflecting area to form a design.

17. In a reflecting sign, a single plate of glass having on one side a reflecting area consisting of a number of prisms, whose opposite sides meet at substantially right angles at their apices and which are adapted to reflect light incident thereon from a distant source back in the general direction of the light source and which have means adapted to slightly spread the reflected light, but concentrate the light within an included angle of twenty degrees, said plate hav-

ing on its other side means for blocking out portions to form a design.

18. In a reflecting sign the combination with a reflecting area consisting of a number of substantially right angled tetrahedra, said tetrahedra adapted to reflect light incident thereon from a distant source back in the general direction of the light source and having means adapted to slightly spread the reflected light but concentrate the light within an included angle of twenty degrees, of means for blocking out portions of the area to form a design.

19. In a reflecting sign, the combination with a reflecting area consisting of a sheet of plate glass on which are formed a number of prisms whose opposite sides meet at substantially right angle at their apices and which are adapted to reflect light incident thereon from a distant source back in the general direction of the light source and which have means adapted to slightly spread the reflected light, but concentrate the light within an included angle of twenty degrees, of means for blocking out portions of the reflecting area to form a design.

20. In a reflecting sign, the combination with a reflecting area consisting of a sheet of plate glass on which are formed a number of substantially right angled tetrahedra, said tetrahedra adapted to reflect light incident thereon from a distant source back in the general direction of the light source and having means adapted to slightly spread the reflected light, but concentrate the light within an included angle of twenty degrees, of means for blocking out portions of the reflecting area to form a design.

21. In a reflecting sign, a plate of glass having on one side thereof a plurality of tetrahedral prisms, said prisms adapted to reflect light incident thereon from a distant source back in the general direction of the light source and having means adapted to slightly spread the reflected light, but concentrate the light within an included angle of twenty degrees, said plate having on its other side an opaque coating disposed to block out a sign substantially as and for the purpose described.

JONATHAN C. STIMSON.
